UNITED STATES PATENT OFFICE

99,074

DESIGN FOR A HAND GUN CARRIER RACK

Ivan L. Eastman, Toledo, Ohio, assignor to The Aro Equipment Corporation, Bryan, Ohio, a corporation of Ohio

Application July 2, 1934, Serial No. 52,418

Term of patent 14 years

To all whom it may concern:

Be it known that I, Ivan L. Eastman, a citizen of the United States and a resident of Toledo, in the county of Lucas and State of Ohio, have invented a certain new, original, and ornamental Design for a Hand Gun Carrier Rack, of which the following is a specification, reference being had to the accompanying drawing, forming part thereof.

The figure is a perspective view of a hand gun carrier rack showing my new design.

I claim:

The ornamental design for a hand gun carrier rack substantially as shown.

IVAN L. EASTMAN.
